JOSEPH PERCY REMINGTON, OF PHILADELPHIA, PENNSYLVANIA, ASSIGNOR TO REMINGTON MANUFACTURING COMPANY, OF PHILADELPHIA, PENNSYLVANIA, A CORPORATION OF PENNSYLVANIA

CARBURETOR

Application filed June 7, 1926. Serial No. 114,297.

My invention relates to carburetion, and to the supply and regulation of air and fuel for internal combustion engines. I aim to improve the operating conditions and efficiency of such engines; to secure a better and more intimate mixture of air and fuel, and more complete vaporization of the latter; to regulate the proportions of air and fuel more correctly; and to insure an adequate supply of the combustible mixture under all conditions. My invention affords the further advantage of permitting the ordinary float controlled carburetor to be dispensed with, as well as the vacuum tanks and the like now so extensively employed. The invention is especially advantageous for motor vehicles, and I have hereinafter explained it particularly with reference to that field of use.

Fig. I is a side view of an air intake and valve mechanism for a motor vehicle engine.

Fig. II is a plan view of the intake and associated parts shown in Fig. I.

Fig. III shows a vertical mid-section through the intake and valves, taken as indicated by the line III—III in Fig. II.

Fig. IV shows a cross-section through the fuel valve, taken as indicated by the line IV—IV in Fig. III, but on a larger scale.

Fig. V shows a fragmentary section through the intake at right angles to Fig. III, taken as indicated by the line V—V in Fig. II.

Fig. VI is a fragmentary side view of certain parts of the valve actuating mechanism, taken as indicated by the line VI—VI in Fig. II.

Fig. VII is a fragmentary perspective view of an adjustable stop device, with a portion of the shaft on which it is mounted.

Figs. VIII—XII are fragmentary dia-grammatic views, similar to Fig. III, illustrating the operation of the device.

Referring to Figs. I and III, it will be understood that in practice the device 15 there shown may be connected at its upper end to the air and fuel intake manifold (not shown) of an internal combustion engine (such as an ordinary motor vehicle engine, not shown), and receives air through openings 18 near its bottom. Liquid fuel (such as gasoline) is supplied through a connection 19

from a reservoir (not shown) mounted, usually, in a position on the car where it is at a lower position than the device 15 when the car is on level ground. It will also be understood that the device 15 is adapted to take the place of the usual carburetor, as well as of the usual hand operated throttle.

As shown in Figs. I, II, and III, the air passage in the device 15 affords a circular seat 21 (formed by a venturi-like narrowing of the passage) for a throttle valve 22, shown as of connoidal and conical "streamline" form. This valve 22 is hollow, being mounted for up and down movement around an upright round tubular fuel supply conduit 23 (Fig. III) that is screwed fast in a bridge piece 24 across the open lower end of the device 15. The opening or mouth 25 at the upper end of the tube 23 may serve as a valve seat for a fuel valve device hereinafter described. The throttle 22 extends above the upper end or mouth of the tube 23, and has at its upper end an opening or mouth 26, somewhat reduced in size, which may also serve as a fuel-valve seat, as hereinafter described.

The throttle valve 22 has a depending guide sleeve extension 27 around the tube 23, with a flange or shoulder 28 at its lower end.

When the engine is stopped, the throttle valve 22 naturally occupies the position shown in Figs. I and III, where it fills the opening in the seat 21 with a close but not tight fit. Even in this position, however, the throttle 22 does not close off the passage completely, owing to some half a dozen vertical grooves 29 in and below its largest portion. When the engine is running, the throttle 22 rises from the position shown in Figs. I and III and floats on the current of inflowing air that is produced by the piston displacement,—as indicated in Figs. VIII—XII. Thus the valve 22 always throttles the inflow of air, and maintains above itself a degree of suction or partial vacuum whose value may be determined by the weight and dimensions of the throttle, or by forcible restraint of its free rise by any means.

From Figs. I and III, it will be seen that the liquid fuel supplied through the conduit 21 is sprayed into the region of suction above 100

the throttle 22, where it is rapidly vaporized under the partial vacuum there existing. For regulating the flow of fuel, there is a valve device 30, here shown as adapted to cooperate (as hereinafter explained) with either of the seats 25, 26 above mentioned. This valve device 30 is movable with and by the automatic throttle 22 with reference to the fuel conduit orifice 25, and is also movable with reference to the throttle 22 and the orifice 26 of the latter. As shown in Fig. III, the valve device 30 has a lower tapering portion 31 for the orifice 25 and an upper tapering portion 32 for the orifice 26. It has also an enlargement or flange 33 above the orifice seat at 25, conically bevelled at its lower side for the purpose of seating tightly on this seat to prevent outflow of fuel when the motor is shut off. Just below the enlargement or head 33, the portion 31 has an abruptly reduced neck 34 extending through and slightly beyond the seat at 25. This neck 34 may be formed by triangular flattening as shown in Fig. IV, so that the shoulders below it may not catch on the edges of the seat 25. As shown in Fig. III, there is a helical compression spring 35 acting between the shoulder at the upper side of the flange 33 and that at the lower side of the throttle seat 26, so as to offer a yielding and progressively increasing resistance to the tendency of suction above the throttle 22 to lift the valve device 30 relatively thereto and to the fuel tube orifice 25. To facilitate assembly and obviate dropping out of the device 30 when the throttle 22 is removed, a pin 36 may be inserted in a diametral hole in the upper end of the portion 32 above the seat 26, as shown.

In operation, the valve device 30 moves up and down with the changes in position of the throttle 22 as already described. Ordinarily, under anything like normal running conditions, the vacuum above the throttle 22 draws the valve device 30 up into the seat 26 until the opening around its upper taper portion 32 is smaller than that in the seat 25 around the lower taper portion 31: i. e., the supply of fuel is ordinarily controlled by the taper portion 32 in cooperation with the seat 26, while the taper portion 31 has no such effect at this time. Accordingly, the effective fuel opening and the fuel supply are varied inversely according to the degree of vacuum above the throttle 22, and, therefore, directly according to the quantity of air flowing to the engine and its demand for fuel i. e., when the absolute pressure above the throttle diminishes, the fuel opening is reduced and vice versa. Also, any change in the pressure of the fuel in the tube 23 (such as results from meeting a steep grade, or from a sudden acceleration or arrest of the car), which would change the fuel flow for a given size of opening, is automatically compensated for by a resulting up or down movement of the

taper 32 in the seat 26. For when the car is on a down-grade, the fuel tank will be elevated, so that there may even be a positive hydrostatic head tending to force the fuel through the opening at 26; but this head will force the valve taper 32 further up into the seat 26, thus reducing the opening and tending to prevent an increase in the flow of fuel. When the car is on an up-grade, the effect is naturally just the opposite. Sudden arrest of the car causes the fuel to rush forward in the supply tank and create a dynamic head of pressure in the supply line 19, with the same effects as when the car is on a down-grade; and sudden acceleration of the car produces an opposite effect. Preferably, the spring 35 is designed to over-compensate: i. e., to be slightly weaker than would be necessary to give the ideal mixture ratio of 0.0625 lb. gasoline to 1 lb. dry air under ordinary conditions, and of such scale as to reduce the richness of the combustible mixture with increasing vacuum (decreasing absolute pressure). Accordingly, the device 15 automatically enables and permits the engine to always select the leanest mixture suitable for its operation under conditions from time to time existing; because if the engine slows and its suction intensity drops on account of the mixture being too lean, the valve taper 30 will be depressed and the effective opening at 26 increased so as to admit more fuel and return the mixture ratio to normal. Preferably, the spring 35 is such as to give a mixture about 25% richer than the above-mentioned ideal for the conditions that obtain in acceleration and hill climbing. As a practical working rule, good results may be secured by selecting and adjusting the spring 35 to comply with these conditions: First, that when the fuel supply tank is elevated from its normal position to the level of the top of the car, the engine can just be idled (or otherwise run unloaded) without stalling; Second, that when the tank is placed on the ground, the mixture supplied the engine when running without load shall be about 25% richer than in the first case.

Under extreme load conditions, on the other hand,—as in accelerating on a steep hill, or towing another car,—the lower tapered portion 31 of the valve 30 may come into effective control of the fuel supply, owing to the great falling off of the vacuum and the consequent depression of the valve 30 by its spring 35. Here, again, the result is a mixture automatically varied in composition,—richer or leaner as is necessary for the best running of the engine under varying conditions.

The rise of the throttle 22 on the inflowing air may conveniently be limited and controlled by means of a stop 40 for engaging the flange 28. As shown in Figs. I, II, III, V, and VII, this stop 40 has the form of

a clevis arm, and is fast on a shaft 41 that is mounted to turn in bosses 42, 42 on the casing walls of the device 15. The shaft 41 may be turned to adjust the stop 40 either 5 by means of a crank arm 43 fast on one end of this shaft 41, with a reach rod or other operating connection 44, or less directly, by means of a crank arm 45 (here shown somewhat longer than the arm 43) at the other end 10 of said shaft 41, mounted to turn (coaxially with the shaft) on a sleeve extension 46 of the corresponding boss 42, and provided with a reach rod connection 47. The shaft 41 and its stop arm 40 are biased counter- 15 clockwise (speaking with reference to Figs. I, III, and VI) by a helical torsion spring 50 around the shaft 41, with one end 51 engaged beneath an arm 52 fast on the end of the shaft, and its other end 53 engaged with 20 a shiftable stop lug 54 that is a part of the arm 45. This spring 50 ordinarily holds the shaft arm 52 against the lug 54 of the arm 45, and thus causes the shaft 41 to follow the movements of the arm 45 as if the arm were 25 actually fast on the shaft; but spring 50 yields, on occasion, to allow the shaft 41 to be turned clockwise by the arm 43. This latter movement of the shaft 41 and its stop arm 40 is limited by engagement of an adjustable 30 stop screw 55 in a lug 56 on the arm 43 against a fixed stop lug 57 on the casing wall of the device 15. As shown, the arm 45 is itself biased clockwise (speaking with reference to Figs. I, III, and VI) by a helical 35 torsion spring 60 mounted around the sleeve 46, with one end 61 engaged beneath said arm 45 and the other end 62 engaged behind a fixed stop lug 63 on the casing wall. Clockwise movement of the arm 45—either by the 40 spring 60, or by the reach rod 47—is limited by engagement of an adjustable stop screw 65 in a lug 66 on the arm 45 against the fixed stop lug 63.

With the relations of parts shown in Fig. 45 III, the stop screw 55 only comes into play to limit clockwise movement of the shaft 41 and its arm 40 beyond the extreme limit of movement permitted the arm 45 by its stop screw 65. In this way, means are afforded 50 for setting the stop 40 to a plurality of definite, independently adjustable positions, according to the adjustment of the screws 55 and 65, so as to suit different conditions of operation of the engine. In addition, the 55 stop 40 can be manually shifted (by means of the arm 45) at pleasure to arbitrarily limit the rise of the throttle 22 and the supply of air and fuel (combustible mixture) to the engine, thus controlling its speed like the 60 manipulation of an ordinary throttle.

In practice, the throttle valve 22 may preferably be so proportioned and of such weight that when floating free and unrestrained it will automatically maintain above it a substantially fixed, constant suction, or partial

vacuum, sufficiently below atmospheric pressure to draw an adequate supply of fuel for the engine under any and all possible conditions of operation, that the engine is capable of meeting, even the most unfavorable. For this purpose, the pressure thus maintained above the throttle 22 should be 70 2 to 4 in. of mercury below atmospheric. In maintaining such a suction above it, the throttle 22 will move up and down with the air stream. Left to itself, the throttle 22 will automatically allow the engine to increase its speed as rapidly as possible (on a combustible mixture at the pressure above indicated) under the load from time to time 75 existing, and to attain the maximum speed of which it is capable under such load; but it will also automatically prevent an injudicious driver from ever stalling the engine by admitting air so freely that the drawing 80 power of the engine at the existing speed cannot maintain sufficient intake suction to draw an adequate supply of fuel to carry the load.

Except in rapid acceleration or under other more or less special load conditions, however, the throttle 22 will rarely or never be thus left to itself to float free on the air stream, for the simple reason that the power of the engine on a combustible charge of the 90 density corresponding to a 4 inch vacuum is greatly in excess of the requirements of ordinary operation. In other words, the driver of the car will naturally—by merely manipulating the reach rod 47 as he has been accustomed to do with the ordinary hand throttle—keep the stop 40 so depressed that the throttle 22 cannot rise enough to give so low a vacuum (i. e., so high an absolute pressure) as 4 inches. The higher vacuum (lower absolute pressure) results in more rapid and complete vaporization of the gasoline or other liquid fuel, and is in that way favorable. On the other hand, when the vacuum is low (high absolute pressure), the speed 95 of the inflowing air is high; so as to vaporize the fuel effectively. And when needed, the self-regulatory action of the throttle 22 to maintain the fixed minimum suction (say 4 in.) required to draw an adequate supply 100 of fuel instantly makes itself felt; for while the driver can close the throttle 22 as much as he likes, he cannot open it, but only free it to open itself as the needs of the engine require. It is impossible, therefore, for the 105 driver to overcharge his engine by opening the throttle wide too suddenly.

The definite maintenance of a minimum intake vacuum by the device 15 as above described not only assures the most rapid pick-up by the engine and obviates risk of killing it by too wide a throttle, but also allows greater engine efficiency than heretofore. In other words, it permits the engine to be designed 115 for a higher degree of compression under 120 125 130

ordinary operating conditions, because it reduces the variation in pressure and quantity of charge as between ordinary conditions and the most extreme conditions of acceleration and hill-climbing: i. e., insures that no greater charge can be admitted at low than at high piston speed. This allows a higher compression ratio because it insures that the engine shall never have a full charge of air at practically full atmospheric pressure to compress, but only air at (say) 4 in. below atmospheric. Accordingly, the engine may have a compression ratio of 1:12, as against about 1:4 in ordinary practice.

Having thus explained the general principles and operation of my invention in the embodiment shown in my drawings, I will not give other particulars of a device that I have used with good results, and also describe in greater detail certain phases of the operation of the device.

The particular device to which I refer has a seat 21 of 1 in. diameter, and a throttle 22 weighing (with its sleeve 27) about 3 oz., and designed to rise $\frac{1}{2}$ in. from the closed position of Fig. III to reach the highest position it is ever expected to attain. The fuel openings 25, 26 are of $\frac{3}{2}$ in. diameter. The fuel valve 30 has a lower portion 31 of $\frac{3}{4}$ in. length below the neck 34, substantially $\frac{3}{2}$ in. in diameter at its upper end, and tapering one degree to the inch on each side; an upper portion 32 of $\frac{3}{8}$ in. length above the head 33, substantially $\frac{3}{2}$ in. in diameter at its lower end, and tapering two degrees to the inch on each side; a neck 34 longer than the width of the seat 25 by about $\frac{1}{16}$ in.; and a total weight of about $\frac{1}{8}$ oz. The tapers 31 and 32 are grossly exaggerated in the drawings, in order to render them visible. Accordingly, this value 30 gives the largest possible passage through the seat 25 when its head 33 is $\frac{3}{2}$ in. off said seat. The spring 35 is of such scale as just to be compressed completely (so as to close its convolutions on one another) by a load of 4 oz., and to expand $\frac{1}{2}$ in. from this condition when entirely relieved of load.

When the engine is shut off, the parts occupy the positions shown in Figs. I and III: with the valve 22 completely closed, as shown in Fig. III; with a clearance of about $\frac{1}{16}$ in. between the lower end of the sleeve 27 and the hub of the bridge 24 in which the tube 23 is mounted; and with the spring 35 compressed only $\frac{1}{2}$ in., so as to expand completely on a $\frac{1}{2}$ in. rise of the throttle 22 from the position shown in Fig. III. Under this condition, the valve head 33 rests on the seat afforded by the fuel orifice 25, closing the latter completely, and the weight of the valve 22 is sustained by the spring 35. The fuel orifice 26, on the other hand, is open practically to its widest, being occupied by the small upper end of the taper 32.

Before the engine is started, the throttle stop 40 is set in the position shown in Fig. VIII by means of the arm 43 and the corresponding stops 55, 57. If desired, the arm 45 may at the same time be set in the position determined by the stops 65 and 63, as shown in Figs. I, II, III, and IX. When the engine is spun to start it, the resulting suction causes a flow of air past the throttle 22, which is thereby lifted. The sub-atmospheric pressure above the throttle 22 due to the engine suction lifts the fuel valve head 33 from the seat 25, thus admitting fuel to mingle with the air stream and form a combustible mixture; whereupon the engine presently starts in the usual manner. When the suction and the consequent rise of the valve 22 have caused and permitted the fuel valve head 33 to rise $\frac{1}{2}$ in. above the seat 25, the maximum fuel opening therethrough is attained, as above described,—without, however, lifting the valve portion 32 anywhere near enough into the seat 26 (which has also risen, of course) to thereby affect the flow of fuel. The setting of the stop 40 above described effectively limits the rise of the throttle 22 and the valve 30 to the positions shown in Fig. VIII, giving a large fuel opening and supply (indeed, substantially the largest possible, as mentioned above), with a very small air opening and a strong suction (10 in. to 12 in. for a self-starter, or 6 in. to 8 in. for hand cranking) above the throttle 22. The result is a "choke" effect, giving a very rich mixture suitable for starting the engine.

When the engine has been started in this manner, the arm 43 is released, and the stop 40 rises to the position of Figs. I, III, and IX,—under the influence of the spring 50, and by virtue of a previous (or concurrent) setting of the arm 45 to the position determined by the stops 65 and 63, as already mentioned. This allows the throttle 22 and the valve 30 to rise until the large end of the lower tapering portion of the latter occupies the seat opening at 25, as shown in Fig. IX. This gives a slightly larger air supply and a still high suction, but a minimum fuel opening and supply, resulting in a lean mixture, suitable for idling and warming up the engine.

In thus idling, the engine usually develops a more or less stable 20 in. vacuum above the throttle 22, which holds the valve 30 high up (as shown in Fig. IX), with its spring 35 fully compressed, and its upper tapering portion 32 pushed up so far into the seat 26 as to give the very least fuel opening that can ever exist with the head 33 off the seat 25. If the resulting mixture proves or becomes so lean as to tend to stall the engine even when idling, then as the engine begins to slow and the vacuum begins to drop (to 18 in. say), the spring 35 expands, pushing the valve end 32 down through its seat 26 so as to increase

the opening and allow a greater supply of fuel,—notwithstanding that the less sharply tapering lower valve end 31 is concurrently pushed further into its seat 25.

5 If the tendency for the engine to stall should be very sudden and severe—owing to the friction of a cold motor and the high viscosity of the cold lubricating oil,—then as the engine suddenly slows and the suction 10 drops off, the spring 35 and the fall of the throttle 22 (due to the reduced suction) lower the valve 30 in the seat 25 until its neck 34 reaches or approximates the priming or choke position described above,—thus giving 15 a few puffs of very rich mixture in time to keep the engine from stalling.

The engine having idled as long as desired, the stop 40 may be set to the positions shown in Figs. X and XI, thus allowing the throttle 20 22 to rise and the air and fuel supply to increase as fast as the speed of the engine can be increased under the load conditions: in other words, the throttle 22 is allowed to float free 25 on the incoming air, and the car is accelerated as rapidly as possible, as already described. As the throttle 22 rises, and the valve 30 with it, the latter gradually increases the effective fuel opening at 25 as the tapering lower portion 31 of the valve rises further and further 30 in the opening, as shown in Fig. X. If, now, the car suddenly encounters a very steep grade, so that the engine speed and suction are suddenly reduced, then the throttle 22 falls to some such position as shown in Fig. 35 XI (while the stop 40 remains raised as there shown), reducing the air supply but maintaining an effective fuel-drawing suction above the throttle. In conditions of moderate suction, the effective control of the fuel 40 may vary between the two ends 31 and 32 of the valve 30, as the load and other conditions affecting the running of the engine and the intensity of the suction above the throttle 22 vary.

45 Fig. XII shows the stop 40 set to limit the rise of the throttle 22 to half open position, and a corresponding position of the valve 30 to give a rather liberal fuel opening and supply at 25.

50 It is to be observed that back fire in the engine will naturally have the effect of driving the throttle 22 downward and compressing the spring 35 until the lower end of the throttle sleeve 27 strikes the hub of the bridge 24; but this will not result in hammering the valve hub 33 on its seat 25, on account of the spring 35.

From the foregoing description, it will be 60 seen that by the automatic action of the floating throttle 22, the intake of air is automatically throttled to a degree at least inversely according to the engine speed and piston displacement,—and even more when the rise of the floating throttle 22 is limited by the stop 40. The admission of fuel by the valve 30 is

also variably throttled according to the relative pressure of the fuel supply and of the throttled air above the valve 22,—by the co-operation of the valve 30 with the seat 26 carried by the throttle 22, as well as by its co-operation with the seat 25 of the fuel conduit 23.

Having thus described my invention, I claim:

1. The combination with the air intake of an internal combustion engine, of an automatic throttle for maintaining therein at least a substantial minimum suction; a conduit for supplying liquid fuel to the region of such suction; a valve device for controlling the flow of fuel responsive to movement of said throttle means, and also movable relative thereto; and other controlling means including a seat carried by said throttle means cooperating with said valve device to vary the fuel passage in response to relative movement of said throttle means and said valve device.

2. The combination with the air intake of an internal combustion engine, of a fuel conduit therein; a valve device movable relative to said conduit to control the flow of fuel; and an air-borne floating throttle for said intake around said conduit affording a passage for fuel therefrom, movable relative to said valve device and thereby cooperating therewith to control the fuel passage, and also actuating said device to move it relative to said conduit.

3. The combination with the air intake of an internal combustion engine, of a fuel conduit therein; an air-borne floating throttle for said intake around said conduit, with fuel passage and a valve seat beyond the conduit mouth; and a valve device cooperating with said valve seat to control the flow of fuel and itself controlled by the intake suction beyond said throttle.

4. The combination with the air intake of an internal combustion engine, of a fuel conduit therein with a valve seat at its mouth; an air-borne floating throttle for said intake around said conduit, with fuel passage and a valve seat beyond the conduit mouth; and a valve device between and cooperating with said valve seats, normally floating on the fuel stream, and yieldingly actuated by said throttle.

5. The combination with the air intake of an internal combustion engine, of a fuel conduit therein with a valve seat at its mouth; an air-borne floating throttle for said intake around said conduit, with fuel passage and a valve seat beyond the conduit mouth; and a valve device with differently tapered portions cooperating with said seats to regulate the flow of fuel, and an intermediate reduced portion cooperating with the conduit seat to give a free initial supply.

6. The combination with the air intake of

an internal combustion engine, of a fuel conduit therein with a valve seat at its mouth; an air-borne floating throttle for said intake around said conduit having a fuel passage and a valve seat beyond the conduit mouth, a 5 valve device cooperating with said latter seat, and also having a flange for closing the conduit mouth and a tapered portion extending into the conduit for cooperating with its seat; and a spring acting between the throttle and 10 said valve tending to seat the latter on the conduit mouth.

7. The combination with the air intake of an internal combustion engine, of a fuel conduit therein with a valve seat at its mouth; 15 an air-borne floating throttle for said intake around said conduit, with fuel passage and a valve seat beyond the conduit mouth; a valve device with differently tapered portions cooperating with said seats to regulate 20 the flow of fuel, a flange between them for closing the conduit mouth, and a reduced portion lying in the conduit mouth when the valve is closed, so as to give a large initial 25 opening; and a compression spring acting between said flange and the throttle.

In testimony whereof, I have hereunto signed my name at Philadelphia, Pennsylvania, this 27th day of May, 1926.

JOSEPH PERCY REMINGTON.
